UNITED STATES PATENT OFFICE.

BERNHARD METZ, OF NEW YORK, N. Y.

DESIGN FOR WATER-PROOF GOODS.

Specification forming part of Design No. 5,429, dated December 19, 1871.

Specification describing a Design for Borders Repellent or Water-Proof Goods, invented by BERNHARD METZ, of New York city, State of New York.

The nature of my design is fully represented in the accompanying drawing, to which reference is made.

A represents a portion of the body of the repellent or water-proof goods, and B a portion of the border. The border consists of fifteen parallel stripes, the middle one being the widest. In the edges of this center stripe *a* I insert teething *c c*, which rest on the narrow stripes inclosing the center stripe. In the two wide stripes *b b*, on the ends of the border, I insert the bars *d d*, which run vertically with relation to the bor-

der; and in the two next stripes, *e e*, I insert other bars, *ff*, which run parallel with the stripes.

I prefer to make the center stripe white, the teething black, the stripes *b b* red, and the bars *d d* white, the stripes *e e* gold, and the bars *f f* black; but I do not consider the colors selected to be essential, and I claim, therefore, the design irrespective of colors.

I claim as my invention—

A design for borders on repellent or water-proof goods, in which the borders are composed of stripes and bars, substantially in the manner shown and described.

Witnesses: BERNHARD METZ.
